CLAIM

The ornamental design for a display screen with graphical user interface, as shown and described.

DESCRIPTION

The FIGURE is a front view of a display screen with graphical user interface showing our new design.

The broken line showing of a display screen shown in the FIGURE is for the purpose of illustrating environmental subject matter and forms no part of the claimed design. The broken line showing of portions of the graphical user interface in the FIGURE forms no part of the claimed design.

1 Claim, 1 Drawing Sheet
